UNITED STATES PATENT OFFICE

115,876

DESIGN FOR A DOUBLE PAPER PLATE CASING

John G. Deynzer, Chicago, Ill.

Application November 29, 1937, Serial No. 73,248

Term of patent 7 years

To all whom it may concern:

Be it known that I, John G. Deynzer, a citizen of the United States and resident of Chicago, in the county of Cook and State of Illinois, have invented a new, original, and ornamental Design for Double Paper Plate Casing, of which the following is a specification, reference being had to the accompanying drawing, forming part thereof.

In the drawing,

Fig. 1 is a top plan view of a double paper plate casing in open position, showing my new design;

Fig. 2 is an end view of the structure shown in Fig. 1;

Fig. 3 is a sectional view on the line 3—3 of Fig. 1; and

Fig. 4 is a side elevation of the plates turned together and forming a casing.

This design is characterized by a double paper plate casing of the configuration shown, the plate members being hinged together along limited portions of adjoining sides as shown, and each portion having formed on the interior face thereof a partition extending upwardly from the bottom and a corresponding depression on the opposite outer face adjacent corresponding ends thereof, the marginal edges of each member being provided with narrow outwardly extending rims and the two members fitting together to provide a flat oval container with opposite corresponding side indentations adjacent one end.

I claim:

The ornamental design for a double paper plate casing, as shown and described.

JOHN G. DEYNZER.
